UNITED STATES PATENT OFFICE.

MORRIS SELIG KHARASCH, OF COLLEGE PARK, MARYLAND.

WATER-SOLUBLE METALLIC ORGANIC COMPOUND AND PROCESS OF MAKING THE SAME.

No Drawing. Original No. 1,589,599, dated June 22, 1926, Serial No. 708,807, filed April 24, 1924.

Application for reissue filed June 16, 1927. Serial No. 199,413.

The present invention relates to the production of organo-metallic compounds which either are themselves water-soluble or have water-soluble salts, or both, and particularly 5 of such compounds in which the metal is bonded to a carbon atom and is of that group of metals, including mercury, arsenic, antimony and bismuth, which, having a valence greater than 1, form organo-metallic 10 compounds stable toward water and with the metal bonded to a carbon atom.

The invention is of particular importance in connection with the organic compounds having germicidal or therapeutic value, such 15 as compounds of mercury, arsenic, antimony, bismuth and the like, the efficiency of which have hitherto been greatly limited by the difficulty of producing readily soluble compounds.

20 In carrying out the process of my invention, I react upon an organo-metallic compound with a suitable organic compound which is either water soluble or has water soluble salts and which contains the thio- 25 hydroxyl group ($-\text{SH}$). The initial organic metallic compound used may have the general formula $(\text{R}-)_{n'} \text{M}(-\text{x})_n$, in which R is any organic group having the metal attached to a carbon atom, x is any replaceable 30 inorganic group of other than the sulphur family, M is any metal which has a valence greater than 1 and which will form organo-metallic compounds stable toward water and with the metal bonded to a carbon 35 atom, and n' and n are each integers greater than zero and at least one less than the valence of the metal. The initial thiohydroxyl compound used is of the general formula $\text{H}-\text{S}-\text{R}_{\text{Ac}}$, in which R_{Ac} is an organic radical containing an acid group and having a carbon atom directly bonded to S; or a soluble salt of the acid shown by that 40 general formula. In other words, the initial thiohydroxyl compound used contains the thiohydroxyl group $-\text{SH}$ with the sulphur atom bonded to an acid-forming organic radical which when so bonded still has a separate valence bond capable of combining with a positive ion—hydrogen or a metal— 45 and which if joined to hydrogen forms an acid or if joined to sodium or potassium forms the corresponding salt. Thus I may use thio alcohols such as ethyl mercaptan,

thioglycerine, or thioglycol, or carboxylic compounds, such as thioglycollic acid, thio- 55 lactic acid, thiomalic acid, thiosalicylic acid, etc., or their salts; or analogous sulfonic compounds; or thiophenols, such as thiore- sorcionol, thionaphthol; and like products.

A typical formula for the initial organo- 60 metallic compounds is as follows: $\text{R}-\text{Hg}-\text{x}$ in which R is any organic radical having the Hg attached to a carbon atom and in which x is any replaceable inorganic radical or group. Hg can be replaced by any metal 65 having a valence greater than one which will form organo-metallic compounds with the metal bonded to a carbon atom and which compounds are stable toward water. These 70 metals are in general those lying lower than hydrogen in the electro-motive series.

By the general process outlined, I may obtain 75 organo-metallic compounds, or salts thereof, of the following general formula:

in which R, M, R_{Ac} , n', and n are as above described. Some of the acids themselves are water-soluble, and all the sodium and potassium salts thereof are water-soluble.

80 The following specific examples illustrate the invention:

Example 1.

Phenyl mercury chloride, $\text{C}_6\text{H}_5\text{HgCl}$, is 85 treated with potassium thio-glycolate, $\text{HSCH}_2-\text{COOK}$. The potassium thioglycolate, which is water soluble, is first dissolved in water, preferably as a concentrated 90 solution. The phenyl mercury chloride is then added to the solution in about the proportion of one mol of the latter to one and one-quarter mols of potassium thio-glycolate in solution. The mixture is gently 95 warmed, preferably with agitation, and the mercury compound passes readily into solution, apparently as the compound having the formula

100

The following reaction takes place

105

To neutralize the hydrochloric acid result-

ing from the above reaction the requisite amount of sodium bicarbonate, NaHCO_3 may be added to the solution. To purify the product thus formed, hydrochloric acid or any other acid may be added. A white precipitate is formed which is

This substance melts, with decomposition, at 164° C. This may be collected on a filter, washed well with water to remove any inorganic salts, dried in a desiccator and then dissolved in the calculated amount of sodium or potassium hydroxide and the whole poured into 95% alcohol. The salt

separates and is collected on a filter. This salt is water-soluble.

Example 2.

To a concentrated water solution containing 0.1 mole of the sodium salt of thiosalicylic acid, the equivalent amount of phenyl mercuric chloride is added and the whole heated for 15 minutes, when the phenyl mercuric chloride goes into solution in the form of

The addition of a small amount of sodium carbonate is quite beneficial for it neutralizes the hydrochloric acid formed in the reaction.

The alcoholic solution is then evaporated to dryness in vacuo. The residue is treated with water and then a small amount of acetic acid is added. The precipitate thus obtained is washed well with water and collected on the filter and then dissolved in the concentrated solution of one equivalent of sodium hydroxide and the whole poured into a mixture of alcohol and ether. The following salt separates:

The compound thus obtained is soluble in water, insoluble in alcohol-ether mixture, insoluble in benzene and other common organic solvents. Upon boiling for a long time in water the solution is broken down. It has no melting point.

Example 4.

To an alcoholic solution of phenyl arsenious chloride an equivalent amount of the potassium salt of thioglycollic acid is added and the whole warmed for about five min-

The compound thus obtained, namely

may be purified by treating the water solution with an acid. A compound

separates which can be collected on a filter and washed free from all impurities. The precipitate can then be dissolved in the calculated amount of a sodium hydroxide solution and the latter poured into 95% alcohol. The product

separates. This product is water soluble.

The salt has no melting point and is insoluble in ether, alcohol, and other organic solvents. When boiled for a long period of time, particularly in concentrated solution, mercuric sulfide separates. The free acid of this salt may be obtained by the addition of any strong acid.

Example 3.

To an alcoholic solution of p-tolyl antimony chloride the equivalent amount of sodium or potassium salt of thioglycollic acid is added and the whole warmed for five minutes on a water bath. The following compound is produced:

utes on a water bath. The following compound is produced:

The compound can be purified in exactly the same manner as outlined in case of the antimony compound given in Example 3, namely the formation of the free acid and the later preparation of the salt. It has no definite physical characteristics.

It is insoluble in most organic solvents; has no definite melting point and decomposes upon long boiling in water solution or with mineral acids.

Minor changes may be made in the steps of the process within the scope of the appended claims without departing from the spirit of the invention.

I claim:

1. The step in the process of producing water soluble metallo-organic compounds which comprises treating with a solution of an organic compound containing a thio-hy- 120

droxyl group directly attached to a carbon atom a compound of the formula $R-M-\alpha$ in which R is any organic radical having the metal attached to a carbon atom, in which α is any replaceable inorganic radical or group, and in which M is any metal having a valence greater than one which will form organo-metallic compounds with the metal bonded to a carbon atom, stable toward 10 water.

2. The method of producing a water soluble metallo-organic compound which comprises treating with a solution of a salt of an organic thio-hydroxyl compound 15 having its thio-hydroxyl group directly attached to a carbon atom and containing an acid group a compound of the formula $R-M-\alpha$ in which R is any organic radical having the metal attached to a carbon atom, in which α is any replaceable inorganic radical or group, and in which M is any metal having a valence greater than one which will form organo-metallic 20 compounds with the metal bonded to a carbon atom, stable toward water.

3. The step in the method of producing a water soluble metallo-organic compound which comprises treating an organo mercuric compound having the formula $R-Hg-\alpha$ 30 in which R is any organic radical having the Hg attached to a carbon atom in which α is any replaceable inorganic radical or group with a solution of an organic thio-hydroxyl compound having its thio-hydroxyl group directly attached to a carbon atom.

4. The method of producing a water soluble metallo-organic compound which comprises treating an organo mercuric compound having the formula $R-Hg-\alpha$ in 40 which R is any organic radical having the Hg attached to a carbon atom in which α is any replaceable inorganic radical or group with an alkaline solution of the thio-hydroxyl organic acid containing also a thio-hydroxyl group directly attached to a carbon atom.

5. A water soluble salt of the following acid $R-Hg.S.CH_2COOH$ in which R is an organic radical having the mercury directly 50 attached to a carbon atom.

6. A water soluble salt of a compound of the following general formula

55 in which R is any organic radical group, R_{Ac} is an organic radical containing an acid group having a replaceable hydrogen ion, M is a metal of a group forming compound stable toward water with the metal bonded 60 to a carbon atom of an organic group and having valence greater than 1, and n is an integer greater than 0 and at least one less than the valence of the metal, the metal and the sulphur in the compound being bonded

to the carbon atoms of the groups R and R_{Ac} respectively.

7. A water soluble salt of a compound of mercury of the following general formula $R-Hg-S-R_{Ac}$ in which R is any aromatic or aliphatic group, R_{Ac} is an organic radical 70 containing an acid group having a replaceable hydrogen ion, the Hg and S atoms being bonded to carbon atoms of the R group and R_{Ac} group respectively.

8. The process of producing a water 75 soluble mercuri-organic compound which comprises treating an organic compound of mercury of the formula $R-Hg-\alpha$ in which R is any organic radical having the mercury attached to a carbon atom and in which α is any replaceable radical or group with a water solution of an alkali metal salt of thio-glycolic acid.

9. The process of producing a water 80 soluble mercury organic compound which comprises treating phenyl mercuric chloride with a water solution of an alkali metal salt of thio-glycolic acid.

10. The step in the method of producing water soluble metallo-organic compounds, 85 which comprises treating, in a suitable solvent, a compound of the formula $R-M-\alpha$, in which R is any organic radical having the metal attached to a carbon atom, α is any replaceable inorganic radical or group, and M is any metal which has a valence greater than 1 and which will form organo-metallic 90 compounds stable toward water and with the metal bonded to a carbon atom, with an organic compound containing a thiohydroxyl group and an acid-forming group and having the sulphur in the thiohydroxyl group bonded to a carbon atom.

11. The method of producing a water 100 soluble metallo-organic compound which comprises treating an organo mercuric compound having the formula $R-Hg-\alpha$, in which R is any organic radical having the Hg attached to a carbon atom and in which α is any replaceable inorganic radical or 105 group, with an organic compound containing a thiohydroxyl group and an acid-forming group and having the sulphur in the thiohydroxyl group bonded to a carbon atom.

12. A compound containing (a) a metal 110 which has a greater valence than 1 and which will form organo-metallic compounds stable toward water with the metal bonded to a carbon atom, (b) an organic radical having a carbon atom joined to such metal by one valence bond of the metal, (c) a sulphur atom joined by one bond to another valence bond of said metal, and (d) an 115 organic-acid-forming group having a carbon atom joined to the other valence bond of the sulphur atom and having a separate bond capable of combining with a positive ion.

13. A compound containing (a) mercury, (b) an organic radical having a carbon atom joined to such mercury by one valence bond of the mercury, (c) a sulphur atom joined by one bond to the other valence bond of said mercury, and (d) an organic-acid forming group having a carbon atom joined to

the other valence bond of the sulphur atom and when so joined being still capable of combining with a positive ion. 10

In witness whereof I have hereunto set my hand at St. Joseph, Buchanan County, Mo., this 13th day of June, 1927.

MORRIS SELIG KHARASCH.
